UNITED STATES PATENT OFFICE

CARL LAUDI, OF DUSSELDORF-GRAFENBERG, GERMANY.

AUTOMATIC GRAB.

1,008,345.

Specification of Letters Patent. Patented Nov. 14, 1911.

Application filed October 15, 1910. Serial No. 587,296.

To all whom it may concern:

Be it known that I, CARL LAUDI, a citizen of Germany, residing at 407 Grafenberger Allee, Dusseldorf-Grafenberg, have invented certain new and useful Improvements in an Automatic Grab, of which the following is a specification.

The present invention relates to that kind of automatic grab in which for the purpose of obtaining a considerable and gradually increasing closing force, the grab jaws which are pivoted to the lower cross bar or axle of the tackle are closed by means of a toggle-lever mechanism. In contradistinction to the known devices of this kind the toggle-lever joint of the improved grab according to the present invention is acted upon by the upper block and the emptying cord or rope, while the free ends of both arms of the toggle-lever mechanism are connected to triangular arrangements of levers which are pivoted to the outer ends of the jaws of the grab and turn on a common axis.

A constructional form of the improved grab is shown in the accompanying drawings by way of example, Figure 1 being an elevation representing the grab in its closed position, while Fig. 2 is a similar representation of the grab in its open position.

30 The two jaws of the grab are pivoted at *a* to the lower cross bar or axle of the tackle. Pivoted to the jaws at *b*, *b* are lever triangles *f*, *g*, *h*, which are adapted to turn about a common axis *c*. The triangles are connected at *d*, *d* to the toggle lever mechanism *e*, *e* which is acted upon at its joint *i* by the upper block of the tackle or an equivalent part and the emptying cord or rope 3.

The automatic opening of the jaws has 10 hitherto been accomplished by the weight of the lower cross bar and part of the weight of the jaws, additional weight being in many cases placed on the cross bar for effecting the opening. An automatic grab should 15 however not only open automatically, but the pull exerted by the cord or rope upon the winding drum of the hoisting apparatus should be sufficient to rotate the drum so as to obviate the necessity of driving the hoisting apparatus backward by motive power. In the improved grab forming the subject of the present invention the whole weight of the grab with the exception of the upper block of the tackle comes into play during 20 the opening, the whole grab being suspended

from the emptying cord or rope 3 at *i* and a particularly strong pulling force is exerted on the toggle levers during the initial period of the opening movement of the grab. These large pulling forces are transmitted 30 to the jaws by means of the lever triangles *f*, *g*, *h* turning upon their axis *c* and are also transmitted to the lifting rope or cord 4 and consequently to the drum of the hoisting apparatus. The drum is thus automatically 35 rotated backward and a saving of motive power and labor is obtained.

In order to obtain the greatest efficiency and the most advantageous filling proportion of the grab the following conditions 40 should be fulfilled: A considerable width of the jaws, a comparatively small weight of the grab proper, a large closing power, an advantageous position of the jaws, and a large opening force.

It will be seen that there are two lifting cords 4 and two emptying cords 3. The lifting cords serve when the grab is in its open position for closing the same, and serve 45 also after closing the grab for lifting the 50 same in its closed position. During the lifting of the closed grab by means of the lifting cords or ropes, the emptying cords are 55 inoperative and remain slack. When the grab is to be opened this is effected by putting the emptying cords under tension and lowering the grab by means of the lifting 60 cords, or by pulling the emptying cords 65 while the grab is suspended from the lifting cords. Of course this means that during 70 the emptying operation the weight of the grab is partly at least suspended from 75 the emptying cords.

I claim:

1. In automatic grabs having jaws pivoted to the lower cross bar of a tackle and actuated by a toggle lever mechanism for the purpose of obtaining a gradually increasing closing force, the combination of a toggle lever mechanism, an upper block 100 of the tackle operatively connected to the joint of the toggle lever mechanism, an emptying cord also connected to the said toggle lever joint, and two lever triangles adapted to turn on a common axis and connected at their outer ends to the ends of the toggle levers and pivoted to the jaws of the grab.

2. In automatic grabs having jaws pivoted to the lower block of a tackle, the com- 110

1,003,845

5 Construction of a lower block, jaws pivoted to the lower block, an upper block, toggle levers pivoted to the upper block, an emptying cord fixed to the upper block, and intermediate parts pivoted to the ends of the toggle levers and the jaws and pivotally connected to each other.

In testimony whereof I have affixed my signature in presence of two witnesses.

CARL LAUDI.
